(57) **CLAIM**

The ornamental design for a garment, as shown and described.

DESCRIPTION

FIG. 1 is a front perspective view of a garment showing my new design;

FIG. 2 is a front view thereof;

FIG. 3 is a side view thereof; and,

FIG. 4 is a rear view thereof.

The long and short broken lines are unclaimed boundaries of the claimed design. It is understood that the claimed design extends to these boundaries but does not include the boundaries.

The even-length broken lines shown in the drawings are directed to environment and form no part of the claimed design.
